UNITED STATES PATENT OFFICE.

FRANK GROCH, OF COBALT, ONTARIO, CANADA.

APPARATUS FOR ORE CONCENTRATION.

1,333,712.

Specification of Letters Patent. Patented Mar. 16, 1920.

Application filed May 19, 1916. Serial No. 98,621.

To all whom it may concern:

Be it known that I, FRANK GROCH, a citizen of the United States, residing in Cobalt, in the Province of Ontario and Dominion of Canada, have invented certain new and useful Improvements in Apparatus for Ore Concentration, of which the following is a specification.

This invention relates to ore concentration in which the metals and metalloids in an ore pulp containing them are separated from the gangue by the selective action of a froth or foam-producing agent, such as oil, which carries the metallic particles to the surface of a bath while the particles of gangue are allowed to settle. By thus separating the values from the gangue the two products may be separately removed and further treated.

20 The object of my invention is to provide improved apparatus for practising a method of concentration of the kind referred to.

In such processes it is important that the ore pulp should be thoroughly aerated in order that the metalliferous particles may be separated from the gangue and that they may be carried to the surface of the bath with the froth-producing agent. I have found that this may be most efficiently done 30 by causing the fluid pulp to be broken up into streams and aerated before it enters the settling vessel.

In one form of the apparatus which I employ the liquid pulp is delivered to a receiving vessel having a perforated bottom through which the pulp passes to a chute which delivers to the settling vat. Air is admitted to the chute below the partition and commingles with the streams of pulp 40 and thus aerates it. In the settling vessel the gangue descends and passes out through a discharge opening while the froth-producing agent rises to the top of the vessel with the metallic values and overflows into an 45 overflow launder. Preferably the settling vessel is provided with means for introducing air or water or both under pressure into its lower portion in order to agitate the pulp and promote the separation of the gangue 50 from the metalliferous particles. I may employ a settling vessel having a flat or horizontal bottom with a central discharge opening in which case I preferably employ slowly rotating arms carrying blades arranged to gently agitate the pulp and to move the settled particles toward the dis-

charge opening of the vessel, or the settling vessel may be conical, in which case the settled particles will automatically move toward the discharge opening and the use of 60 rotating discharging apparatus is not required.

My improvements are illustrated in the accompanying drawings, in which—

Figure 1 is a view mainly in vertical section of apparatus which may be employed in the practice of my invention.

Fig. 2 is a plan view of the perforated partition between the pulp-receiving vessel 70 and the chute which delivers to the settling vat.

Fig. 3 shows a vertical section of a modified form of apparatus.

Referring to Fig. 1, A indicates a settling vat having an overflow launder *a* and a central discharge opening *a'* which is formed in a central depressed portion *a²* of the vat.

B indicates arms carrying blades *b* for gently agitating the pulp and for moving the settled material toward the depressed portion or well *a²*. The arms *B* are attached to a vertical shaft *B'* which is driven by suitable mechanism *B²* of ordinary construction. Fluid pulp from the mill or plant is delivered through a trough or conduit *C* to a receptacle *D*, separated from the chute *E* by a perforated partition *F*. The chute and receptacle may be supported on the vat *A* by brackets or supports *G*. The partition *F* is preferably, but not necessarily, concavo-convex and it is provided with a multiplicity of openings *f* which are preferably made square, as indicated in Fig. 2. The partition rests on a flange *f'* 75

in the receptacle *D* and has a central opening *f²* for the shaft *B'* which extends vertically through it and also through a sleeve *f³* connected with the partition and which prevents fluid from passing around the shaft into the chute. The receptacle *D* is 80

provided with an overflow launder *d* connected by a pipe *d'* with the chute below the partition so that should the fluid pulp rise 85

so high in the receptacle *D* as to overflow it will not be wasted but will pass through 90

the pipe *d'* into the chute and thence into the vat. Ordinarily, however, the fluid level is maintained in the receptacle *D*, as indicated in the drawings. Air is introduced into the chute below the partition by 95

means of pipes *I* which are preferably of considerable length and extend vertically, 100

105

110

as indicated. The fluid pulp is continuously supplied through the trough C to the receiver D and it flows through the openings f and through the chute in streams 5 which so subdivide the pulp that the air introduced through the pipes I is thoroughly commingled with it, and the pulp enters the settling vat in a thoroughly aerated condition. It will be understood that a froth- 10 producing agent, such as oil, is mixed with the pulp either at the plant or in the vessel D or with less good results it may be added to the pulp in the settling vat. In either case a foam rises to the top of the settling 15 vessel and overflows to the launder a with the metallic values. The gangue settles to the lower portion of the settling vessel and is discharged through the central opening therein. The air or water introduced into 20 the lower portion of the settling vessel promotes the operation.

The settled material passes through the opening a' and out through a discharge pipe N provided with a valve or gate P for regulating the discharge. 25

In Fig. 3 I have shown apparatus similar in most respects to that shown in Fig. 1 except that the rotary apparatus for moving the settled material to the discharge opening is dispensed with. In this case the settling vessel A' is cone-shaped and discharges through a central opening a' to which the settled material gravitates automatically. In other respects the construction and operation of the apparatus are the same as that indicated in Fig. 1 and the parts are similarly lettered. 30 35

I claim as my invention:

1. Apparatus for aerating pulp, comprising a chute, a pulp receiving vessel above the chute, a perforated partition between the vessel and the chute for sub-dividing the pulp into thin streams which pass in such condition through the chute, a pulp containing vessel into which the chute projects and whose liquid level is above the lower end of the chute, and a pipe communicating with the upper portion of the chute below the partition through which air from the atmosphere passes into the chute. 50

2. Apparatus for aerating pulp, comprising a vertically arranged chute, a pulp receiving vessel above the chute, a perforated partition between the vessel and the chute for sub-dividing the pulp into thin streams, which pass in such condition through the chute, a pulp containing vessel into which the chute projects and whose liquid level is above the lower end of the chute whereby the chute is sealed at its lower end against the entrance of air therethrough, a pipe communicating with the upper portion of the chute below the partition through which air is drawn from the atmosphere into the chute, an overflow trough for the pulp receiving vessel, and a pipe leading from said overflow trough to the chute. 60 65

In testimony whereof I have hereunto subscribed my name.

FRANK GROCH.
